UNITED STATES PATENT OFFICE.

FREDERICK J. WEBER, OF LOS ANGELES, CALIFORNIA.

INCINERATOR.

Application filed October 29, 1923. Serial No. 671,347.

To all whom it may concern:

Be it known that I, FREDERICK J. WEBER, a citizen of the United States, residing at Los Angeles, in the county of Los Angeles, 5 State of California, have invented a new and useful Incinerator, of which the following is a specification.

This invention relates to the construction of incinerators and relates particularly to 10 incinerators especially adapted for domestic use.

With the passage of ordinances respecting the burning of refuse and waste materials throughout the various large cities, it has

15 become necessary to provide means in compliance with such ordinances in which the refuse may be burned. A common type of incinerator consists of a vertical structure of fire resisting material having an opening 20 near the upper end thereof through which the material to be burned is placed in the incinerator and an opening near the bottom thereof serving as a draft opening and for the removal of ashes. Such incinerators are 25 not generally made of such size to receive a very large charge and as the material placed therein burns, it is customary to add thereto through the charge openings. It is found that when the fire is burning within 30 the incinerator and the charge door is opened, flames and smoke will issue therefrom in a manner making the addition of more material unpleasant and often causing burns to the person.

35 It is an object of the invention to provide a grate and draft system suitable for use in an incinerator having a charging opening with a suitable cover, a draft opening having a closure plate, and intervening mechanism for causing the movement of the closure plate across the draft opening when the charging door is opened, thus shutting off the air from the incinerator so as to cause the flames therein to die down and 40 thus eliminate the undesirable and dangerous issuance of smoke and flame from the charging opening.

45 It is a further object of the invention to provide novel features contributing to the simplicity and economy of construction.

50 It is a further object of the invention to

provide an incinerator so constructed that a clean out door extending the full width of the incinerator may be provided, thus giving ample room for the removal of ashes from 55 the bottom of the incinerator and permitting the grate and grate supporting structure to be entirely removed from the interior thereof. Owing to the packing of the material placed in the incinerator for burning, 60 a free upward circulation of air for combustion is often seriously interfered with so that an excess volume of smoke and the charring of the materials to be burned results.

65 My invention may be used with auxiliary air channels in the side walls through which air is delivered from the ash chamber to points above the packed combustible material so that more complete combustion 70 takes place and the production of smoke is reduced to a minimum.

75 It is a further object of the invention to provide a grate and draft system suitable for use in an incinerator which may be cast in the form of separate parts, thereby facilitating its transportation, which when set up will interlock in the form of a rigid structure.

80 The especial advantages and further objects thereof will be made evident hereinafter.

Referring to the drawings which are for 85 illustrative purposes only:

Fig. 1 is a perspective elevation of one type of incinerator in which I may embody the features of my invention.

Fig. 2 is a vertical section taken substantially upon a central plane.

Fig. 3 is a section taken on a plane indicated by the line 3-3 of Fig. 2.

Fig. 4 is a view taken as indicated by the arrow 4 of Fig. 3, but with the clean out door and the door lintel removed.

Fig. 5 is a fragmentary enlarged section 95 taken as indicated by the line 5-5 of Fig. 1.

Fig. 6 is a perspective view of the grate supporting member.

The incinerator shown in Fig. 1 comprises a lower box structure 11, an upper box structure 12, a cap 13, and a stack 14 which are placed one upon the other and are of such 100

form that they interlock without use of bolt means and provide an incinerator chamber in which refuse may be burned without fire hazard and without the objectional features of an open trash fire.

In the incinerator shown, the lower section 11 is formed of four quadrilateral slabs in 16, 17, 18 and 19 which are preferably cast from concrete, although other cementitious mixtures may be employed. These slabs which rest upon front corner foundation members 20 and rearward foundation members 21, are provided with edge formations such as shown at 23, Fig. 3, so that a seal may be formed therebetween by the use of a layer of asbestos material 24 or other similar fire resisting substance. The members 16 and 18 have channels 26 cast in the edges thereof and the edges 27 of the members 17 and 19 are suitably beveled to fit the channels 26, thus providing a bending of the sheet of asbestos 24 into angular form when placed between the members 16 to 19. The lower edges of the side members are held together by the upwardly extending walls 30 of the foundation members 20 and 21, and a frame 31 also cast of concrete is placed over the upper edge of the wall members. This frame or ring 31 is recessed at 33 and 34 so that it will fit down over the upper edges of the members 16 to 19 and will receive the lower edges 35 of the wall members 37 constituting the upper section 12. The upper edges of the wall members 37 are enclosed by the downwardly extending flanges 38 of the cap 13 which is of conoidal form and has an upwardly projecting internal flange 40 over which the lower end 41 of the stack 14 rests. The wall members 37 have the same edge construction as the wall members 16 to 19 and are placed together with strips of insulating material in the same manner as previously described.

The wall 16, as best shown in Fig. 2, extends only part way down from the top edge of the lower section 11 so that the clean out opening 44 which is the full width of the section 11 is thereby formed, and which opening resting upon foundation members 21, is normally closed by a door plate 45, having a handle 46. In view of the fact that the edges of the wall members slope inwardly, it is evident that the door member will remain in place without the use of securing means.

In this form of incinerator, the wall 18 is provided near its lower edge or at its lower edge with a draft opening 47 provided with a closure plate 48 operating in vertical slides 49. The front plate 37 of the upper section 12 is provided with a charging opening 39 encircled by a suitable frame 50. Supported across the upper edge of the opening by bearing blocks or clamps 51 is a shaft 52 to which the upper edge 53 of the charging

door 54 is secured. The leftward end of the shaft 52 is bent laterally and provided with an eye 56 so that a crank 57 will be formed. From the eye 56 of the crank 57 a chain 59, or other flexible member, extends 70 downwardly over a pulley 61 mounted in the leftward side 62 of the frame 31 as shown in Figs. 1 and 5, to the closure member 48, this chain being of such length that when the crank 57 is in upwardly extending 75 position, the closure plate 48 is raised as shown in Fig. 1, thus allowing the passage of air through the draft opening 47 when the charging door is closed. A foot lever 64 is hinged at 65 to the member 18 and a chain 80 67 is extended therefrom over the pulley 61 and connected to the chain 59 at 68. A downward application of pressure on the lever 64 is indicated by the arrow 69 which causes the chain 59 to be pulled downwardly 85 with the result that the crank 57 is rotated through an arc 71 causing the door 54 to swing upwardly and allowing the closure plate 48 to drop down in the slides 49 so as to close the draft opening. This arrangement of parts causes the draft to be shut off when the charging door is opened, thus preventing the issuance of a blast of flame and smoke from the charging opening, therefore making it possible to safely and conveniently place additional refuse in the incinerator.

Coming now to those features of novelty to whose protection the present application is especially directed, as shown in Figs. 2, 3 and 4, a grate support 75 is placed in the bottom of the lower section 11 which has the form shown in Fig. 6, a one-piece grate 76 being disposed thereacross for the purpose of supporting the materials placed in the 105 incinerator.

The member 75 is comprised of an upper U-shaped frame 77 having inwardly directed horizontal walls 78, from the inner edges 79 of which there downwardly and outwardly 110 extend side walls 81 which slope outwardly in such a manner that the lower edges 82 thereof are disposed vertically below the outer edges of the U-shaped supporting frame 77. When the member 75 is in place, with its central or leg-connecting portion disposed opposite the opening 47, or its equivalent V-shaped channels, Fig. 2, are provided between the lower portions of the wall members 17 to 19. Air passages such as the perforations 84 are provided in the sloping walls 81, through which the air which has entered through the draft opening 47 into the channels may pass inwardly to the central portion of the grate 76 as indicated by the arrows 87 in Fig. 2.

In the walls 17, 18 and 19 may be formed air channels 89 which extend from points below the grate 76 to points 90 somewhat above the grate level. When a considerable 130

quantity of material is placed in the incinerator for burning, the first four or five inches thereof resting on the grate may become very tightly packed due to the weight 5 of the superposed material, thus interfering with the passage of air necessary for combustion. The optional air channels 89 or their equivalent, however, permit air to pass freely into the upper portion of the fire 10 chamber so as to produce combustion in the upper layers of the material. The air drawn through these passages 89 may be derived from the same source as the air which passes through the grate member and may be therefore controlled by the closure plate 48. 15

The plate 16, when employed in connection with the described features of my invention, serves as a lintel for the clean out opening, and may be provided as shown in Fig. 3, 20 with lugs 94 at the upper edges thereof which extend into recesses 95 formed at the upper corners of the members 17 and 19, thus supporting weight of the member 16 on the side walls 17 and 19. For the purpose of securing the plate 16 against being swung outwardly, a flat bar 100, Fig. 4, may be riveted or bolted to the inner face of the member 16, the ends 101 thereof being constricted to round bar form projecting through holes 102 25 and having nuts 103 threaded thereon as shown. By removing the member 45 which is the full width of the lower section, ample opening is provided through which the grate support and grate may be removed with a minimum of effort so that all metal particles, 30 cans, and other such articles may be cleaned from the grate and the ashes quickly dragged out with a hoe or other suitable instrument. This constitutes a valuable feature over the 35 present construction of incinerators owing to the fact that such incinerators are not provided with suitable means for cleaning out the ashes or unburnable articles therein but can only be cleaned by fishing the ashes 40 out through the draft opening or through the top of the charging opening of the incinerator. 45

Although I have herein described a complete incinerator, various features thereof 50 constitute the subject matter of separate applications Serial No. 40,270 filed June 29, 1925 the features upon which protection is herein sought being more particularly indicated in the following claims.

55 I claim as my invention:

1. In an incinerator, a combination of: side walls defining a fire chamber; a grate disposed across said chamber at an intermediate level; and a member U-shaped in horizontal outline and provided with perforations in its upper part, said member forming V-shaped air passages between a draft opening in the lower portion of said chamber and a central space beneath said grate, 60 whereby air for sustaining combustion is 65

conveyed, by way of said V-shaped passage and by way of said perforations, into contact with the material on said grate.

2. In an incinerator, the combination of: 70 side walls defining a fire chamber; a one-piece grate disposed across said chamber at an intermediate level and removable through a side thereof; and a grate-supporting member insertable through said side and forming substantially V-shaped air passages from which ash is excluded, said grate-supporting member comprising downwardly divergent inclined walls having apertures near the top thereof, whereby air for sustaining combustion is conveyed upwardly to the material on 75 said grate. 80

3. In an incinerator, the combination of: 85 side walls defining a fire chamber and a draft opening; a grate disposed across said chamber at an intermediate level; and an air distributing grate support provided with substantially flat horizontal top surfaces and with apertures whereby air for sustaining combustion is conveyed to the material on 90 said grate, a movable closure member for said draft opening being arranged to control the flow of air to said grate through said support, and said grate and said support being freely removable. 95

4. In an incinerator, the combination of: 100 side walls defining a chamber and having a draft opening near the plane of their lower edges; and a grate disposed across said chamber in an intermediate position, said side walls having substantially vertical air 105 passages formed therein and extending between the lower portion of said chamber divided off by said grate and the upper portion of said chamber, whereby air for sustaining combustion will be conveyed upwardly around the material on said grate; and a closure member for said draft opening arranged to shut off the flow of air through said grate and said passages. 110

5. In an incinerator, the combination of: 115 side walls defining a burning enclosure; a grate in said burning enclosure for supporting material to be burned; and a grate supporting member having a central opening and downwardly extending supporting walls, 120 said walls being spaced away from said enclosure walls so as to provide an air channel, and having perforations therein through which air may pass from said air channel to said central opening of said grate supporting member. 125

6. In an incinerator, the combination of: 130 side walls defining a burning enclosure; a grate in said burning enclosure for supporting material to be burned; and a grate supporting member having a central opening and downwardly extending supporting walls enclosing a portion of the lower end of said enclosure as an ash chamber, said walls being spaced away from said enclosure walls 130

so as to provide an air channel, and having perforations near the upper edges thereof through which air may pass from said air channel to said central opening of said grate supporting member.

7. For use in an incinerator comprising a grate in a burning enclosure provided with a lateral draft opening; a substantially U-shaped air distributing grate support com-

prising laterally perforated and downwardly divergent side walls constituting legs connected by a central portion and which is adapted to be so disposed relatively to said opening as to admit air beneath said grate.

In testimony whereof, I have hereunto set my hand at Los Angeles, California, this 20th day of October, 1923.

FREDERICK J. WEBER.
